UNITED STATES PATENT OFFICE.

CALVIN W. LITTLE, OF DENVER, COLORADO.

DESIGN FOR A WATCH-CHAIN AND ATTACHMENT.

SPECIFICATION forming part of Design No. 13,181, dated August 15, 1882.

Application filed June 27, 1882. Term of patent 7 years.

To all whom it may concern:

Be it known that I, C. W. LITTLE, of Denver, in the county of Arapahoe and State of Colorado, have invented and produced a new and original Design for Watch-Chains and Attachments, of which the following is a specification, reference being had to the accompanying drawing, forming part thereof, in which is shown an elevation of my watch-chain and attachment.

The strip of metal A, made of equal width throughout its entire length, is doubled upon itself twice, in such manner that the link shall have two loops, a b, opening at right angles to each other, and each extending from one end of the link to the other. The link thus constructed has four nearly-equal sides with each two opposite sides converging toward each

other at one end, and the two pairs of opposite sides converging thus at opposite ends 20 from each other.

The attachment B is made to resemble a mail-bag with loops c d at the top and bottom respectively.

What I claim, and desire to secure by Letters Patent, is—

The design for a watch-chain, consisting of the links having the loops a b, constructed as above described, and the attachment B, resembling a mail-bag and having loops c d, substantially as specified.

CALVIN W. LITTLE.
